SLICING MACHINE

Filed July 3, 1929

UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed July 3, 1929. Serial No. 275,603.

My invention relates to a slicing machine of the type in which a rotary knife is driven, preferably by motor, at relatively high speeds. One object of my invention is to provide means for protecting the transmission and particularly the belt drive of such a knife from the access of grease, dirt, meat particles and the like. Other objects will appear from time to time in the course of 10 the specification and claims.

I illustrate my invention more or less diagrammatically in the accompanying drawings, wherein—

Figure 1 is a front elevation with parts 15 broken away;

Figure 2 is a section on the line 2—2 of Figure 1; and

Figure 3 is a detail.

Like parts are indicated by like symbols 20 throughout the specification and drawings.

Referring to the drawings, A generally indicates any suitable base upon which is mounted the motor A¹ with the motor shaft A² and its pulley A³.

25 B is a rotary knife the front of which is recessed as at B¹ and the rear as at B². B³ is a knife shaft upon which the knife is mounted and B⁴ is a pulley associated with knife and shaft. B⁵ is a driving belt passing 30 about the pulleys B⁴ and A³.

The knife shaft is mounted in any suitable bearing, for example in the sleeve portion C mounted on the frame or base A. It includes the bearing portion proper, C¹, and

35 a bell shaped guard extension therefrom, C², the edge of which penetrates the recess B², as shown in Figure 2. C³ indicates a housing partition or wall associated with the sleeve C, apertured as at C⁴ to permit the 40 passage therethrough of the pulley A³. The wall C³ is provided with a forwardly extending flange or wall C⁵ in proper shape to surround the drive, its general form being indicated, for example, in Figure 1. With the

45 wall C³ protecting one side of the transmission and the wall C⁵ extending forwardly from it and the knife itself, in cooperation with the guard C², protecting the pulley, I provide a further, and removable partition 50 or housing member generally indicated as D.

It may be secured to the wall C⁵, as by the screws D¹. It is secured to the lower portion of the guard C², or to an adjacent portion of the housing, as at D². It will be observed that it penetrates substantially within 55 the periphery of the knife and its inner edge may, if desired, be provided with a flange or rim D³, approaching or entering the recess B². Under ordinary circumstances this flange or rim may be dispensed with, but 60 under some circumstances it may be useful. In order to provide space for the motor shaft and the pulley A³ the member D may be outwardly offset as at D⁴. When it is necessary to have access to the transmission, as when 65 it is necessary to change the belt I may remove the knife, as by removal of its securing screw C¹⁰. When the knife is removed the screws D¹ D² may be loosened and the plate D can then be removed.

In order further to limit the access of material to the interior of the knife housing I provide the guard plate E, the arcuate edge E¹ of which penetrates the forward recess B¹ of the knife. The knife axis is tilted, as shown in Figure 2, in order to throw the cutting edge of the knife forwardly into the plane of the guard plate E. E² is any suitable scraper, which may be mounted on the guard plate E, which engages the forward face of the knife and further reduces the tendency of material, grease and the like, to be carried into the interior of the knife housing.

It will be realized that whereas I have described and shown a practical and operative device, nevertheless many changes might be made in the size, shape, number and disposition of parts without departing from the spirit of my invention. I therefore wish my 85 description and drawings to be taken as in a broad sense illustrative and diagrammatic rather than as limiting me to my specific showing.

The use and operation of my invention are 95 as follows:

In the slicing machine of the type herein shown it is advantageous to employ a belt of rubber. In slicing fatty meats, grease or lard fries out of the cold bacon or ham. 100

Similarly, in cutting other meats, for example, hot meats, the juices are carried about the periphery of the knife. The rubber in the belt deteriorates seriously if any such grease, lard or juices, reach it. This condition is particularly disastrous with rubber belts, but belts of any material, such as leather, when such are used, are likely to deteriorate. And finally, regardless of the deterioration of the belts, and even where other driving means are employed, it is extremely disadvantageous to have grease, lard, meat juices, fragments and scraps of meat carried into the interior of the device. They not only interfere with the drive, but develop an unsanitary condition. In the present knife most of the grease, lard and the like is scraped off by the scraper E² so far as concerns the front of the knife. The little that remains may be carried on the periphery of the knife into the interior of the knife housing and to the rear of the guard plate E. It cannot reach the transmission or go any farther because the partition D, which overlaps the knife, forms a complete closure for the transmission housing formed by the walls C³ and C⁵. Owing to the speed of rotation of the knife any such grease, juices and fragments if discharged from the knife, are thrown centrifugally from the knife edge. They cannot crawl back in toward the knife axis and therefore cannot penetrate the space to the rear of the partition D. The partition D and wall C⁵ further prevent particles from the sharpening elements G G¹ when in use, to enter the transmission.

I claim:

1. A slicing machine including a rotary knife and a motor adapted to drive the knife, a removable guard plate for the forward face of the knife, pulleys associated with knife and motor and a driving belt connecting them and shielding means adapted to prevent the access to said belt of material cut by the knife, including a removable shield element, between knife and belt, overlying the belt and the motor pulley and extending a substantial distance within the periphery of the knife and toward its axis of rotation.
2. In a slicing machine, a motor, a rotary knife, a driving connection between knife and motor, a guard plate adapted to mask the forward face of the knife, and a removable partition member, to the rear of said guard plate, positioned between the knife and the said driving connection.
3. In a slicing machine, a motor, a rotary knife, a driving connection between knife and motor, a removable guard plate for the forward face of the knife, and a separately removable partition plate, to the rear of said guard plate, intermediate the knife and the driving connection.
4. In a slicing machine, a motor, a rotary knife, a driving connection between knife and

motor, a removable guard plate for the forward face of the knife, and a separately removable partition plate, intermediate the knife and the driving connection.

5. A slicing machine including a knife and a motor adapted to actuate it, a removable guard plate for the forward face of the knife, a transmission intermediate said knife and motor, and shielding means adapted to prevent the access to said transmission of material cut by the knife, which includes a removable shield element positioned between the knife and transmission and extending a substantial distance within the periphery of the knife and overlapping the face of the knife.

6. In a slicing machine which includes a knife and means for actuating it, and a motor therefor, a transmission intermediate said knife and motor, a housing adapted substantially to enclose said knife, said transmission being positioned within said housing, and interior guard means, within said housing, positioned between said transmission and said knife.

7. In a slicing machine, a motor, a rotary knife, a driving connection between knife and motor, a guard plate adapted to mask the forward face of the knife, and a removable partition member, to the rear of said guard plate, positioned between the knife and the motor.

8. In a slicing machine which includes a rotary knife, a motor therefor and a transmission between knife and motor, a guard plate adapted to mask the forward face of the knife and an intermediate protecting plate interposed between the rear face of the knife and the transmission, said intermediate plate, overlapping the face of the knife and terminating between the periphery and the axis of the knife.

Signed at Indianapolis, county of Marion and State of Indiana, this 27th day of June 1929.

WILLIAM J. CAMPBELL.
